Inventor,

Leonard E. Renfro,

By A. D. Jackson

Attorney

Witness

John E. Milton.

UNITED STATES PATENT OFFICE.

LEONARD E. RENFRO, OF FORT WORTH, TEXAS.

BUSHING EXTRACTOR AND INSERTER.

1,369,544.

Specification of Letters Patent. Patented Feb. 22, 1921.

Application filed September 2, 1919. Serial No. 821,146.

To all whom it may concern:

Be it known that I, LEONARD E. RENFRO, a citizen of the United States of America, residing at Fort Worth, in the county of 5 Tarrant and State of Texas, have invented certain new and useful Improvements in Bushing Extractors and Inserters, of which the following is a specification.

My invention relates to a tool for extracting and inserting inner sleeves or bushings of various types, and the object is to provide an inexpensive tool which will be highly efficient in extracting bearing sleeves or guiding sleeves and bushings, such as 15 motor vehicle sleeves, sleeves for aeroplane motors, electric motor bearings, locomotive link pin bearings, brass sleeves of water pumps, and any kind of bearing, and also for inserting such bearings. Other objects 20 and advantages will be fully explained in the following description and the invention will be more particularly pointed out in the claims.

Reference is had to the accompanying 25 drawings which form a part of this application.

Figure 1 is a side elevation of the invention herein set forth, and a section of such devices on which the improved tool operates. Fig. 2 is an end view of the wicker-head. Fig. 3 is a side elevation of the same. Fig. 4 is a detail view of the spring which holds the wicker-head assembled. Fig. 5 is a side elevation of an extension for the 35 mandrel or screw shaft. Fig. 6 illustrates a variation of the wicker-head expander. Fig. 7 illustrates a split washer to be used as shown in Fig. 6. Fig. 8 illustrates the tool used for inserting a bushing or bearing. Fig. 9 is a vertical section, showing a variation of the tool used as an inserter.

Similar characters of reference are used to indicate the same parts throughout the several views.

This invention includes a threaded pull bar or mandrel 1 which has an expanding member 2 which terminates with a shouldered head 3. A wicker-head, consisting 45 preferably of three segments 4, 5, and 6, is mounted on the pull rod 1 and operates on the expanding member 2. The wicker-head or gripping member 4, 5, and 6, has an annular groove 7 and an open ring

spring 8 holds the parts 4, 5, and 6 on the pull rod and permits the wicker-head to 55 drop down on the expanding member 2 until the wicker-head comes in contact with the inner wall of a sleeve 9 or bushing which is held by the housing 10. The object of the tapering form of the expander 2 is to make 60 the parts 4, 5, and 6 of the wicker-head grip the inner sleeve or bushing for removing the same. The wicker-head is adapted for gripping purposes by cutting annular angular grooves in the periphery thereof 65 and making relatively sharp edges 11 for gripping the inner wall of the sleeve or bushing to be removed.

The manner of using the tool for extracting purposes is shown in Fig. 1. The tool 70 is adjusted over the sleeve and the tapering or expanding member is inserted. Then the wicker-head or gripping member is allowed to drop down on the expander till the gripping edges 11 engage the inner wall 75 of the sleeve. A sleeve or spacing member 12 is then placed on the housing of the sleeve or bushing and a washer 13 is placed as a bearing on the support 12. A nut 14 is then screwed down on the mandrel or pull 80 bar 1 against the washer 13. This will draw or pull the sleeve 9 out of the housing 10. If a longer mandrel or pull bar is required, an extension mandrel 15 may be provided and connected to the bar 1 by a coupling 16. 85

In order to prevent the wicker head 5 from dropping too far down in the sleeve or bushing 9, annular grooves 17 may be cut in the periphery of the expanding member 2 and split washers 18 inserted to stop the 90 wicker-head. The grooves 17 may be located wherever needed.

For inserting a sleeve or bushing, the parts of the tool are reversed in action. Fig. 8 illustrates how the tool may be used 95 for inserting a sleeve or bushing. The wicker-head 5 rests against the shoulder 3 and the washer 13 rests on the housing 10 or other support. The upper end of the wicker-head engages the sleeve or bushing 100 and the nut 14, when turned, will draw the wicker-head against the sleeve 9 and force the same into the housing 10. Various modifications and applications of the improved tool may be made without departing 105 from my invention. The tool 19 shown

in Fig. 9 has stepped shoulders and each shoulder would answer for a different sized sleeve or bushing.

What I claim, is,—

- 5 1. A sleeve extractor comprising a pull-rod or mandrel having a threaded portion and an expanding portion, a cylindrical head in segments mounted on said pull-rod, a nut operating on the threaded portion of 10 said pull-rod, a spring for holding the segments of said head yieldingly on said pull-rod, and positive means for positioning said head at different points on said expanding portion.
- 15 2. A sleeve extractor and inserter comprising a pull-rod having a threaded portion and an expanding portion and having a head on the end of said expanding portion integral therewith, a cylindrical head in

segments mounted on said pull-rod and provided with an annular groove in the periphery thereof, a spring in said groove for holding said segments yieldingly on said pull-rod, and a nut operating on the threaded portion of said pull-rod. 20

25 3. A sleeve extractor comprising an expandible head, a pull-rod having a threaded portion and an expanding portion and annular grooves in said expanding portion, carrying said head, a nut operating on the 30 threaded portion of said pull-rod, and split washers carried in the said grooves for limiting the movement of said head on the expanding portion of said pull-rod.

In testimony whereof I set my hand, this 35
25th day of August, 1919.

LEONARD E. RENFRO.
